(57) CLAIM

The ornamental design for a dining chair, as shown and described.

DESCRIPTION

FIG. 1 is a front perspective view of a dining chair, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 2.

The evenly dashed broken lines in the drawings illustrate portions of the dining chair, which form no part of the claimed design. The dot-dash broken lines illustrate the borders of the enlarged detailed view and form no part of the claimed design.

1 Claim, 9 Drawing Sheets
